UNITED STATES PATENT OFFICE.

SYLVAIN DREYFUS, OF DENTON, NEAR MANCHESTER, LANCASTER, ENGLAND.

APPARATUS FOR EFFECTING THE CONTINUOUS CONCENTRATION OF SULFURIC ACID.

1,217,577.

Specification of Letters Patent. Patented Feb. 27, 1917.

Application filed January 10, 1917. Serial No. 141,724.

To all whom it may concern:

Be it known that I, SYLVAIN DREYFUS, a subject of the King of Great Britain and Ireland, and a resident of Denton, near Manchester, in the county of Lancaster, England, have invented certain new and useful Improvements in Apparatus for Effecting the Continuous Concentration of Sulfuric Acid, of which the following is a specifica-
tion.

In the manufacture of certain explosives sulfuric acid of high percentage is necessary and up to now most of this has been obtained by enriching H_2SO_4 , 168 Twaddell (92 to 15 93%) with oleum. The object of the present invention is to obtain a sulfuric acid of high percentage without the use of oleum, and with simple apparatus made of cast iron.

According to the invention, I take advantage of and adopt two known principles, viz.: (a) that 90 to 93% sulfuric acid does not attack cast iron, and (b) that in the process of concentrating sulfuric acid the higher percentage of the acid is always at the bottom of the apparatus. In combination with these said principles, I also take advantage of and adopt the further known principles, (c) that water is eliminated from sulfuric acid only gradually, and (d) that such gradual evaporation may be obtained by letting the acid to be concentrated travel, while heated, an extended distance, either through many vessels, as by the cascade, or 35 as in other known processes.

In carrying out the invention, I employ apparatus made of cast iron and comprising an outer pan and an inner pan or pans and also a cylinder or cylinders, or, in place of 40 pans and cylinders, the said outer pan is fitted with internal divisions, the arrangement in either case being such that the acid has to take a circuitous up and down path before it reaches the outlet. The said ar-
rangement is also such that the concentrated acid always flows from the bottom of the apparatus before being drawn off. The apparatus is heated externally in any suitable manner. Within such apparatus I place, up 45 to the level of the overflow, concentrated sulfuric acid of a strength which will not affect the cast iron. The acid to be concentrated is then admitted to the apparatus,

the concentrated acid being simultaneously run off in corresponding quantities. The 55 weak acid will, of course, be admitted at a rate suitable for the required concentration.

The resulting effect of such method or process of concentration is that a sulfuric acid of high percentage, (95% and above) 60 may be obtained, and in a continuous manner. A further effect is that the acid can be obtained, using a cast-iron apparatus of comparatively simple construction and small 65 size.

The accompanying drawings illustrate, in cross-sectional elevation, various examples of the improved apparatus.

The apparatus illustrated in Figure 1 consists of a cast-iron pan *a* wherein is situated a further and smaller cast-iron pan *b* supported by say cast-iron feet *b*¹ upon the floor of the pan *a*. Depending into the pan *b*, and reaching almost down to the bottom of the pan, is a cast-iron cylinder *c*. Closing 75 the upper end of the pan *a* and cylinder *c* is any suitable form of cover, in which are inlet pipe *d* and vent pipe *e*. Upon the exterior of the pan *a* is the overflow pipe *f*. Below and around the apparatus are the 80 usual fire *g* and flue passages *h*.

In starting the process the pan *b* is first charged to the level of its top edge, and the pan *a* is charged to the level of the overflow with the concentrated acid of such 85 strength (say 90 to 93%) as will not injure the cast iron, and such acid is heated to the required temperature. The acid to be concentrated is then run into the apparatus through pipe *d*, and the concentrated 90 acid is run off through the overflow pipe *f* into any suitable cooling apparatus. In flowing through the apparatus the acid has an extended traverse, first flowing downward, then upward, then downward again, 95 and finally upward through the overflow pipe.

The process can be carried on continuously by introducing into the cylinder *c* the weak acid to be concentrated and running off the concentrated acid in corresponding quantities.

Holes *c*¹ are provided to allow the products of evaporation to reach the vent pipe *e*.

The apparatus shown in Fig. 2, is similar to that shown in Fig. 1, except that a

cylinder *c* is arranged between the two pans *a* and *b*, instead of within the pan *b*, and the pipe *d* extends down into the pan *b*. Further, the overflow pipe *f* is at the top of the apparatus.

The apparatus shown in Fig. 3 differs from Figs. 1 and 2 in that two cylinders *c*, *c* are used. The overflow pipe *f* is at the top of the apparatus.

10 In Fig. 4, the apparatus therein shown comprises two inner pans *b*, *b* and three cylinders *c*, *c*, *c*, and the overflow pipe *f* is at the top of the apparatus.

In the apparatus shown in Fig. 5, the pan 15 *a* is fitted with cast-iron cylinders *c*, *c* only, certain of which depend from the cover or lid of the apparatus, while certain others rise from the floor of the apparatus, the depending cylinders alternating with the cylinders rising from the floor. The overflow

20 pipe *f* is arranged at the top of the apparatus.

What I claim and desire to secure by Letters Patent is:—

Apparatus for the continuous concentration 25 of sulfuric acid to 95% and upward, comprising a cast-iron vessel, means for heating said vessel, a plurality of cylindrical divisions in said vessel communicating with each other at the top and bottom alternately and forming a circuitous path leading to the bottom of said vessel, means for introducing weak acid to the interior of the innermost of said divisions, an outlet for the concentrated acid 30 leading from the bottom of said vessel, and means for venting the products of evaporation.

In witness whereof I have hereunto set my hand.

SYLVAIN DREYFUS.
